FACADE FOR A CAR WASH BUILDING, OR SIMILAR STRUCTURE

Roberto E. Fabrizio, La Habra, Calif., assignor to Rheem
Manufacturing Company, New York, N.Y., a corpora-
tion of California

Filed Sept. 18, 1964, Ser. No. 81,783

Term of patent 14 years

(Cl. D13—1)

FIGURE 1 is a front perspective view of a facade for a car wash building or similar structure showing my new design;

FIGURE 2 is a rear elevational view thereof.

The broken lines in the drawing are shown only for illustrative purposes.

I claim:

The ornamental design for a facade for a car wash building or similar structure, substantially as shown and described.
